UNITED STATES PATENT OFFICE.

JAMES McNAMARA, OF MONTREAL, QUEBEC, CANADA, ASSIGNOR TO MERRANTHALER LINOTYPE COMPANY, A CORPORATION OF NEW YORK.

MONOLINE-MACHINE.

No. 856,898.

Specification of Letters Patent.

Patented June 11, 1907.

Application filed March 5, 1907. Serial No. 360,798.

To all whom it may concern:

Be it known that I, JAMES McNAMARA, a citizen of the United States, residing in Montreal, in the Province of Quebec, Dominion of Canada, have invented a new and useful Improvement in Monoline-Machines, of which the following is a specification.

My invention has reference to that class of machines for casting slugs or printing bars which are commonly known under the trade mark "Monoline", and represented as to their general organization in Letters Patent of the United States No. 506,198, and also in more improved form in application for Letters Patent of the United States filed by me on the 14th day of July, 1905, Serial No. 269,748.

In this class of machines, the matrices, each containing several characters in the vertical edge, are dropped one after another into a composing box in which they are individually arrested at different levels, to bring the selected characters to the alining level, and thereafter delivered laterally from said box to the end of the line which is being composed, the matrices in the composed line being retained individually at the proper heights by a horizontal assembling rail or bar, which enters notches in their edges.

As the composed line increases in length, it is advanced against a yielding resistant while the successive matrices at the rear end are carried past and retained by spring pawls or dogs.

In the course of composition it is frequently desirable to remove the last matrix from the line either because the line is composed to an excessive length or because an undesirable character has been accidentally set in the line.

In the machine as originally constructed, the detaining devices which held the matrices at the rear end of the line were of such form and were housed in or covered in such manner that the removal of a matrix was attended with much trouble and loss of time.

The object of the present invention is to overcome this difficulty and provide for the instantaneous release of the last matrix so that it may be speedily removed, and to this end it consists broadly in combining with the matrix-retaining devices means whereby they may be disengaged and held for the time being out of action.

In the accompanying drawings I have shown my improvement in the form adapted for use in the machine represented in my application Serial No. 269,748, before referred to, and with the exception of the parts specifically described herein, the machine may be in all respects identical with that described in said application, but it is to be understood that the details may be variously modified without changing the mode of action or passing beyond the limits of my invention.

In the drawings,—Figure 1 is a front elevation of the composing-box and adjacent parts with my improvement incorporated therein. Fig. 2 is a side elevation of the same looking from the left. Fig. 3 is a horizontal section on the line 3—3 of the preceding figures, with the parts in the normal or operative positions. Fig. 4 is a similar view with the parts adjusted to release the last matrix. Fig. 5 is a plan view on an enlarged scale, of parts shown in the preceding figure.

Referring to the drawings, 1, 1, represent the matrices each consisting of an elongated bar having a suspending hook at the upper end, a series of intaglio characters or matrices in one vertical edge, and a corresponding series of alining notches in the opposite edge. These matrices, bearing different groups of characters, are stored in a magazine and delivered one at a time therefrom through intermediate mechanism by finger-keys representing the various characters and spaces. The matrices are delivered downward in an endwise direction behind a glass door or guide 12*, into the assembling box 4, beside an upright front-plate 32. They are arrested at different heights by stop-devices controlled by the respective finger-keys.

Each matrix, after being arrested with the designated character at the alining level, is maintained temporarily by a horizontally swinging bridge-plate 29, which enters one of the notches in the rear edge of the matrix, as shown in Fig. 2. This bridge, when in engagement with the matrix, forms a continuation of the horizontal fixed assembling rail 28 upon which the matrices are pushed one after another by the action of the reciprocating pusher 26, the plate 32 being automatically withdrawn in a rearward direction before the pusher advances.

The advancing line acts against and is held in compact order by the horizontally yielding resistant 49. As the successive matrices are added to the rear end of the line, the line is 5 advanced bodily along the line-race and rail 28, and retained by spring-actuated detents 40. These detents are shown in the form of dogs or pawls turning on vertical pivots 40^a and beveled at the receiving end so that they 10 will yield as the matrices are forced between them and immediately engage behind the last matrix.

So far as described, the parts above referred to are constructed and arranged to operate in the same manner as the parts indicated by like numerals in application #269,748.

Referring now to the parts which form the subject-matter of my invention, it is to be 20 noted that their purpose is to withdraw the forward detent 40 momentarily from engagement with the last matrix in the line, so that the matrix 1 may be turned from its normal position, shown in Fig. 3, backward away 25 from the line, as shown in Figs. 4 and 5, after which it may be lifted out of the machine.

It will be observed that when the matrix is thus turned horizontally away from the line in the course of its removal, it leaves the 30 remaining matrices in engagement with the rail 28, so that there is no danger of their falling out of position or below their proper heights.

Instead of constructing the matrix-supporting bridge 29 as heretofore, I now provide it at one end with a lip or projection 29^a, adapted to engage the end of the matrix-detent 40, so that when the bridge is swung backward from the operative position, shown 40 in Fig. 3, to the position shown in Figs. 4 and 5, beyond the field of the descending matrices, it will act upon the end of the detent 40 and throw the latter back out of engagement with the matrix line. With the parts 45 in this position, the operator may readily grasp the last matrix and turn it away from the line and out of engagement with the rear detent 40, as shown in Figs. 4 and 5, after which the matrix may be withdrawn from 50 the machine, the whole operation being practically instantaneous.

For the purpose of throwing the bridge backward and holding it in position to keep the front detent 40 out of engagement, I 55 pivot to the frame the lever 29^b arranged to act at one end against the bridge 29. This lever stands normally in the position shown in Fig. 3, permitting the bridge to operate substantially as in the original machine. 60 When, however, the lever is turned to the position shown in Figs. 4 and 5, it causes the bridge and the detent 40 to swing backward and locks them in position. This action is due to the fact that the co-acting ends of the 65 bridge 29 and lever 29^b are eccentric to their

pivots, and so formed that when the lever begins its movement, its extremity will first cause the bridge to swing backward or outward around its pivot until it assumes the position shown in Figs. 4 and 5, after which 70 the continued movement of the lever causes its end to abut against the extremity of the bridge, as shown, so as to hold the same in position.

In order to permit the removal of the matrix at any time, it is necessary to insure the withdrawal of the front-plate 32 before the detent 40 is disengaged. In order to effect this action automatically, I provide the glass door or guide 12^a at the lower end with a projection 12^b to act against a sliding plate 12^c mounted on the frame. This plate, which is slotted and guided by screws 12^d, is so formed that it will engage at the rear end with the sliding rod 33, which carries the front-plate 85 32, as heretofore.

When the door is closed and the parts are in normal position, the plate 32 is free to move automatically forward and backward as usual, but when the door 12^a is opened to give access 90 to the internal parts, the projection 12^b pushes the plate 12^c backward and causes the withdrawal of the plate 32, thus leaving an unobstructed space through which the matrix may be removed. When the door is closed, 95 the parts automatically resume their positions.

While I have described my invention in that form which I consider best adapted for use in the monoline machine, it is to be understood that the form and arrangement of the parts may be modified to any extent within the range of mechanical skill, provided they have a mode of action substantially such as stated.

I believe myself to be the first to combine with detents to retain the matrices added to a line in course of composition, means of any kind for withdrawing either of the detents, and the first to combine with a detent means 100 for holding the same out of action so that the matrix at the end of the line may be conveniently removed.

While I have shown my invention in a monoline machine, it is obvious that it may 115 be used in any analogous machine in which a composing mechanism delivers matrices successively to retaining devices or detents at the end of the line.

The lever 29^b may be restored by hand to 120 its normal inactive position, but in order to save time and relieve the operator, I prefer to arrange the lever in the path of the usual horizontally vibrating yoke 37, employed to return the stops, as heretofore.

The glass plate or door 12^a which swings horizontally is held normally in the closed position by an overlying latch 12^f pivoted to the frame to swing vertically. A spring 12^g under the rear end of this latch presses its 130

ward end downward over the front edge of the door. It is to be observed that the shoulder of this latch bearing against the door is inclined or beveled. This is for the purpose of permitting the door to swing open automatically whenever pressure is exerted against its inner face by descending matrices or spacers which are lodged against one another or which are otherwise thrown out of position.

The holding of the door in such manner that it will swing open under moderate pressure is a new feature in this class of machines, and it is to be understood that the catch may be modified in form at will provided only that it is adapted to release the door under the conditions stated.

Having described my invention, what I claim and desire to secure by Letters Patent is:

1. In a monoline machine, matrices each containing a series of characters and alining notches, means for delivering the matrices successively to a common line of one height or another, as demanded, means for sustaining the matrices at the proper height, a yielding detent to engage and hold the successive matrices as they are added horizontally to the line, and a manual device for operating the detent at will to disengage it from the last matrix; whereby the ready removal of the matrices by a turning and lifting movement may be effected.

2. In a matrix composing machine, means for assembling the matrices horizontally in line, means for maintaining the individual matrices at one height or another in the line, as demanded, yielding detents to hold the successive matrices as they are added to the line, and means for throwing one of said detents out of action independently of the other at will.

3. In a composing mechanism, a yielding detent to engage the successive matrices as

they are added to the line, and mechanism for disengaging the detent at will and locking it out of action.

4. In a monoline machine, the combination of notched matrices, a movable bridge to temporarily sustain the matrices as they are advancing toward the line, a detent to retain the matrices at the end of the line, the bridge being arranged to throw the detent out of action.

5. In a monoline machine, the combination of notched matrices, the fixed rail 28, swinging bridge 29, and the yielding detent 40, arranged to be thrown out of action by the bridge.

6. In a monoline machine, and in combination with the notched matrices, means for assembling the same in line, a detent to engage and hold the last matrix in the line, a reciprocating front-plate 32, and means for moving the front-plate and the detent away from their operative positions to release the end matrix; whereby the ready removal of said matrix from the machine is permitted.

7. In a monoline machine, and in combination with the reciprocating front-plate 32, the swinging door 12^a, and intermediate devices actuated by the door to cause the retreat of the plate.

8. In a monoline machine, and in combination with the reciprocating front-plate 32, the door 12^a, and the intermediate slide 12^b.

9. In a monoline machine, and in combination with the detent 40, the bridge 29 acting thereon, and the lever 29^b arranged to move and lock the bridge.

In testimony whereof I hereunto set my hand this twenty-fifth day of February, 1907, in the presence of two attesting witnesses.

JAMES McNAMARA.
